UNITED STATES PATENT OFFICE.

CHARLES B. H. LA BOUNTY, OF TACOMA, WASHINGTON.

NON-REFILLABLE BOTTLE.

1,076,129.

Specification of Letters Patent. Patented Oct. 21, 1913.

Application filed April 3, 1913. Serial No. 758,662.

To all whom it may concern:

Be it known that I, CHARLES B. H. LA BOUNTY, a citizen of the United States, residing at Tacoma, in the county of Pierce 5 and State of Washington, have invented certain new and useful Improvements in Non-Refillable Bottles; and I do declare the following to be a full, clear, and exact description of the invention, such as will enable 10 others skilled in the art to which it appertains to make and use the same.

This invention relates to bottles and jars, and more especially to those which have valves in their necks to prevent them from 15 being refilled; and the object of the same is to produce an improved guard in the shape of a cap covering the outlet end of the neck so that liquid cannot be passed thereinto in order to refill the bottle, with im- 20 proved means for preventing the removal of said guard. This and other objects are carried out in the manner hereinafter more fully described and claimed, and as shown in the drawings wherein—

25 Figure 1 is a vertical section of this improved bottle in an upright position, and Fig. 2 is a similar section with the bottle inverted. Fig. 3 is a cross section on the line 3—3 of Fig. 1. Fig. 4 is a perspective 30 view of the nipple at the upper end of the bottle-body. Fig. 5 is a sectional perspective view of the cap on a larger scale.

In the drawings the letter B designates the body of an ordinary bottle, although of 35 course the same might be a jar or a jug, and the letter N designates the neck thereof which in the present instance is comparatively large and surrounds a smaller neck *n* which is in effect a nipple upstanding within 40 the axis of the larger neck from a trans- verse partition T which is molded of glass at the time the bottle is formed. The inner neck is small and short, and permits the insertion of an ordinary cork in the upper 45 end of the outer neck or shield, so that the bottle may be laid away or transported as usual. The nipple *n* is tubular, and through it the contents of the bottle are poured out as usual; and it is the purpose of the present 50 invention to cover said nipple with a guard in the shape of a cap, movably attached to the nipple so that it cannot be removed by those who are maliciously inclined, and so constructed that the contents of the bottle 55 may be decanted but the bottle cannot be refilled.

Coming now more particularly to the details of the present invention, the numeral 1 designates a rather wide groove around the nipple where it emerges into the parti- 60 tion T, and the numeral 2 designates a pair of grooves leading from said wide groove 1 upward at quite a steep pitch around the nipple and open at its upper end as shown. In the drawings I have illustrated two of 65 these spiral grooves 2, but it is quite obvious that a greater or lesser number might be em- ployed. The numeral 3 designates ratchet teeth or barbs formed in the walls of the spiral grooves 2, and having their tips pro- 70 jecting downward, and the exact disposition of these barbs is unimportant although I would prefer that they be sharp.

The cap is a cup-shaped member of any 75 suitable material having a cylindrical body 5 and a closed and slightly concave upper end 6. The bore of said body is preferably provided with longitudinal grooves 7, and at opposite points, if there are two of the spiral grooves 2 as shown, said bore carries 80 two inwardly projecting pins 8, each of which has a groove in its upper side 9 so that in effect it is U-shaped in cross section where it projects into the bore of the cap.

The parts are assembled as shown in Fig. 85 1, and before the cap is applied the bottle is filled. Then the cap is dropped in place and its body turned until its pins engage the upper ends of the grooves 2, when it will travel downward if the bottle is jiggled slightly 90 and come to rest with its pins in the wide groove 1. The mouth of the larger neck N is closed with a cork, and the bottle is sent to its destination; and when it is desired to decant the bottle the cork C is withdrawn 95 and the bottle turned to a horizontal position. The result is that the liquid flows down through the nipple *n* against the inside of the cap 5, and pushes the latter outward on the nipple until its pins strike the upper 100 side wall of the wide groove 1. If it should so happen that they pass into the lower or inner ends of the wide grooves 2, they quickly come to rest when their pins 8 en- gage the barbs 4. In fact it would be almost 105 impossible to remove the cap from the nip- ple, even if one could catch hold of the cap which is impossible by reason of the proxim- ity of the outer neck N. The liquid flow- 110 ing outward through the nipple passes into the upper end of the cap, then returns through the longitudinal grooves within its

bore, and flows out the outer neck. When the liquid is poured out and the bottle is empty, the parts resume the position shown in Fig. 1. When now it is undertaken by some unauthorized person to refill the bottle and the same is stood up, liquid poured into the larger neck rises in the lower end thereof of above the partition T and around the nipple *n*, and the air trapped in the cap causes the latter to rise as far as its pins permit and then produces in effect an air seal so that the liquid will not enter the nipple *n*. The relative sizes and exact details are not essential.

15. What is claimed as new is:

1. The combination with a cap of inverted cup-shape, and pins projecting radially inward within its bore; of a bottle having a neck rising from its upper end, and a tubular nipple rising from said end within such neck and having external spiral grooves extending from its lower end upward and provided with downwardly projecting barbs in their walls, the grooves being so disposed as to receive the pins in the cap.

2. The combination with a cap of inverted cup-shape, and pins projecting radially inward within its bore; of a bottle having a partition across its neck, and a tubular nipple rising from and opening through said partition and having an annular groove around its base and spiral grooves extending from said annular groove to its upper

end and having downwardly projecting barbs in their upper walls, the last-named grooves being so disposed as to receive the pins in the cap. 35

3. The combination with a cap of inverted cup-shape, and pins projecting radially inward within its bore at the lower end of the latter, each pin being of U-shaped cross section; of a bottle having a neck rising from its upper end, a tubular nipple rising from said end within such neck and having an annular groove around its base and spiral grooves extending from said annular groove to its upper end and having downwardly projecting barbs, the last-named grooves being so disposed as to receive the pins in the cap. 40

4. The combination with a cap of inverted cup-shape, and a pin projecting radially inward within its bore and of U-shaped cross section at its inner end; of a bottle, a tubular nipple rising from it and having a spiral groove extending from its lower to its upper end and provided in its upper wall with a downwardly projecting barb. 45

In testimony whereof I have hereunto set my hand in presence of two subscribing witnesses. 50

CHARLES B. H. LA BOUNTY.
